UNITED STATES PATENT OFFICE.

ALBERT KLELL, OF WEST PARK, OHIO.

AUTOMOBILE RADIATOR.

Application filed April 17, 1918, Serial No. 229,171. Renewed January 17, 1923.

To all whom it may concern:

Be it known that I, ALBERT KLELL, a citizen of the United States, residing at West Park, in the county of Cuyahoga and 5 State of Ohio, have invented certain new and useful Improvements in Automobile Radiators, of which the following is a specification.

This invention relates to an improvement 10 in an automobile radiator, and the object is to provide a radiator having a plural number of water-circulating sections or units which may be removed separately merely by unscrewing two nuts exposed at the front 15 of the radiator body. Each unit consists of a column of disk cells of square outline, and each cell is divided into two compartments by a perforated diaphragm, thus causing the water to flow in a thin stream from the 20 center to the edge of each cell and back to the center and thence into the next cell over a similar circuitous course and so on through the column.

In the accompanying drawings, Fig. 1 is 25 a front view of a radiator constructed according to my invention, but showing only one-half of its full complement of water-circulating units removed, and Fig. 2 is a sectional view of the top and bottom portions of a radiator body with the water-circulating units removed, and Fig. 3 is a sectional view of one of the units, but shown shortened by omission of central cells. Fig. 30 4 is a side view of the radiator, partly in section, showing the units fastened in place. Fig. 5 is an enlarged sectional detail of one cell showing the walls and diaphragm separated. Fig. 6 is a plan view of a cell dia- 35 phragm.

40 The radiator comprises an open frame consisting of two water-distributing compartments 2 and 3 which are rigidly united together in spaced relation by narrow side walls forming a frame, in a sense, within 45 which the radiator units are adapted to be removably secured. The bottom compartment 2 has a water outlet connection 5 at its rear, and top compartment 3 is provided with a water intake connection 6, also at its 50 rear. Each compartment 2 and 3 has a channeled or hollow offset 7 at its rear extending inwardly which provides a vertical seat or wall 8 transversely of the radiator, and the respective offsets project toward 55 each other and provide a recess in the front face of the radiator adapted to receive a

series of water-circulating and cooling sections or units 12. Thus, the heads 10 and 11 at opposite ends of each water-circulating unit 12 may be seated upon the retired wall 8 and a watertight joint made thereat by placing suitable rubber gaskets 13 between the meeting faces of the assembled parts. The means for clamping each unit in place, consists of a bolt 14 extending through a tube 15 within each offset 7, and the bolt is either screwed or seated in place and extends forward beyond the front face of the radiator. In this way, each unit may be easily slipped into place from the front and also easily removed. The heads or ends of each unit are hollow and each has a central tube 17 extending therethrough from front to rear, and a recess or pocket 18 is formed in the front face of each head to receive 75 the nut 16.

When assembled, the hollow interior of each unit head and the compartments 2 and 3 are open to each other for a free flow of water, and a pair of nipples 19 is provided 80 in wall 8 adjacent each bolt 14, each nipple having a flange secured to the inner side of the wall 8 and being projected forwardly to enter suitable openings in the rear flat wall of each head, and which openings necessarily correspond in position to that of the 85 nipples.

Each water-circulating unit 12 is a built-up or composite structure, consisting of the hollow heads or ends 10 and 11 built into a 90 column of disk cells 21, having short necks sleeved and united together. Each cell comprises two dished parts 22 and 23 of concavo-convex formation seamed together, and I insert a thin metal plate 24 centrally between the said parts. This plate has a row of perforations 25 in its border and the body of the plate is also provided with rounded projections 26 struck up in opposite directions on radial lines, and these projections 100 space the outer walls or sections 22 and 23 in definite distances apart and also prevent complete collapse thereof. Each cell is made of thin metal, and the diaphragm 24 having projections as described is of advantage in reinforcing the cell. The cell parts 22 and 23 have each a short neck, 27, whereby a sleeved union may be made with an adjacent disk cell of similar construction, in this way building up a column of such disk cells 110 through which the water is adapted to circulate in a circuitous course beginning at the

center of each disk cell and passing to the outer edge thereof, thence through the perforations in the diaphragm and back through the upper chamber to the center of 5 the cell where communication is established with the next adjacent or superposed disk cell.

The water circulating unit as thus constructed is strong and durable, and also 10 sufficiently flexible to withstand any expansion or contraction to which it may be subjected, and it is also well adapted to withstand the shocks and vibrations met with when used in an automobile radiator. I 15 have shown the disk cells as square so that a solid bank of such cells may be placed in close juxtaposition within the open frame of the radiator, and when so placed each disk cell is separated slightly from the next 20 and air spaces are provided from front to rear of the radiator and all of the cell surfaces are exposed to the cooling influence of the air passing through the radiator.

What I claim is:

25 1. A radiator comprising separate water compartments at its top and at its bottom having sheet metal walls offset inwardly to provide transverse recesses and vertical seats facing the front side of the radiator and 30 water passages therein at the rear side of said recesses and seats, said vertical seats having a series of elongated depressions therein and a plurality of spaced openings at the base of each of said depressions, in combination with separate water circulating units having hollow end portions seated in said recesses and provided with openings at their rear sides corresponding in position and number to the openings at the base of

each of said depressions, nipple projecting 40 through a pair of said openings in each depression, re-enforcing tubes extending through said offset walls rearwardly of said depressions, elongated gaskets seated within said depressions, and clamping bolts extending through said reenforcing tubes centrally between each pair of openings adapted to secure the units detachably in place.

2. A radiator comprising an open frame having hollow water compartments at its 50 top and bottom, the walls thereof being made of sheet-metal and offset angularly to provide transverse water passages and vertical seats and transverse recesses at the front side of said passages, said seats each having 55 a series of elongated depressions therein and the base of each depression having a pair of water circulating openings therein and a bolt opening centrally between said water-circulating openings, bracing tubes 60 rearwardly of said depressions opposite said bolt-openings sealed at their ends to the interior of said transverse water passages and gaskets seated within and confined at 65 their edges by the border walls of said depressions, in combination with vertical water-circulating and cooling units having hollow end compartments and openings in the rear walls thereof corresponding in position to said water-circulating and bolt 70 openings in said seats, and clamping bolts for each unit extending through said bolt openings.

Signed at Cleveland, in the county of Cuyahoga, and State of Ohio, this 1st day 75 of April, 1918.

ALBERT KLELL.
